UNITED STATES PATENT OFFICE.

OTTO DANDER, OF KÖNIGSBERG, GERMANY.

WOOD-POLISHING MACHINE.

No. 871,111.

Specification of Letters Patent.

Patented Nov. 19, 1907.

Application filed May 24, 1907. Serial No. 375,559.

To all whom it may concern:

Be it known that I, OTTO DANDER, a subject of the German Emperor, and resident of Königsberg, Germany, have invented certain new and useful Improvements in Wood-Polishing Machines, of which the following is a specification.

This invention relates to a wood polishing machine with which all the movements necessary for an exact and proper polishing can be made.

The accompanying drawing shows the machine embodying the invention.

Figure 1 is a side view, and Figs. 2 & 3 a plan, of the same, the latter two figures showing respectively how the machine is used for effecting an elliptical or rectilinear movement of the polishing tool; Figs. 4 & 5 are respectively a vertical section through, 20 and plan of, a detail of the machine on an enlarged scale.

On the frame *a* the vertical shaft *e* is mounted and adapted to be actuated by the pulley device *b* and the toothed bevel gearing *c, d*. From the shaft *e* the pulley *f* keyed on the same, is actuated, which transmits its movement by means of a belt *g* to a pulley *h* which is keyed on the vertical shaft *i*. At the upper end of the latter the crank disk *k* is arranged and provided with the crank bolt *k'* which engages the slot *l* of the support member *m*. The latter is connected with the support *n* by means of the screw *o*. The support *n* is movable in lateral direction 35 and guided in the guiding ledge *p*. The screw *o* engages with its upper part the slot *q* of the rod *r* and moves the latter to both sides. To the rod *r* the connecting-rod *s* may be firmly attached by means of two 40 screws *t*. The connecting-rod *s* is actuated by the adjustable crank pin *u* and crank *v* which is centered on the vertical shaft *e*. In the front end of the rod *r* the polishing tool *w* is fixed and connected with two chambers 45 *x* and *x'*. The weight *y* provided on the rod *r* serves to regulate the pressure of the polishing tool on the wood to be polished. In the cross member *z* of the frame *a* a hole *z'* is provided in which a guiding bolt may be inserted.

The operation of the machine is as follows:— To effect elliptical movements of the polishing tool, the rod *r* is firmly attached to the connecting-rod *s* by means of the two screws 55 *t* so that by actuating the driving mechanism

the tool *w* describes an elliptical way.—On the other hand, the rectilinear movement of the tool *w* is obtained by simply taking one of the screws *t* out so that the rod *r* is only pivoted to the connecting-rod *s*, and inserting it through the slot *q* and the hole *z'* in the cross member *z*. Into the chambers *x* and *x'* the polishing medium—shellac and spirit—is filled and supplied to the polishing tool *w* through the medium of a regulating device.

Having fully described my invention, what I claim and desire to secure by Letters Patent is:—

1. A wood polishing machine comprising in combination with the frame, the crank driving mechanism, a connecting-rod attached to the latter, a crank transmission mechanism actuated by said crank driving mechanism, a slotted rod firmly attached to said connecting-rod and connected with said crank transmission mechanism, the polishing tool (*w*) attached to the free end of said slotted rod, two chambers to supply said tool with the polishing medium and provided for this purpose with a regulating device, and a weight provided on said slotted rod to regulate the polishing pressure of said tool, all for the purpose of effecting an elliptical movement of said tool.

2. A wood polishing machine comprising in combination with the frame, the crank driving mechanism, a connecting-rod attached to the latter, a crank transmission mechanism actuated by said crank driving mechanism, a cross member of said frame provided with a hole, a bolt inserted in the latter hole, a slotted rod pivoted to said connecting-rod and connected with said crank transmission mechanism as well as with said bolt, the polishing tool (*w*) attached to the free end of said slotted rod, two chambers to supply said tool with the polishing medium and provided for this purpose with a regulating device, and a weight provided on said slotted rod to regulate the polishing pressure of said tool, all for the purpose of effecting a rectilinear movement of said tool.

In testimony whereof I have hereunto set my hand in the presence of two subscribing witnesses.

OTTO DANDER.
